MOTOR DRIVEN SHOE POLISHER

Frank J. Di Sesa, Jr., Lombard, Ill., assignor to Sunbeam Corporation, Chicago, Ill., a corporation of Illinois

Filed June 8, 1965, Ser. No. 85,614

Term of patent 14 years

(Cl. D9—2)

Fig. 1

Fig. 2

Fig. 3

Fig. 7

Fig. 4

Fig. 5

Fig. 6

FIG. 1 is a perspective view of a motor driven shoe polisher viewed from the front showing my new design;

FIG. 2 is a side view thereof when viewing FIG. 1;

FIG. 3 is a bottom view thereof;

FIG. 4 is a perspective view thereof viewed from the rear;

FIG. 5 is a top view thereof;

FIG. 6 is a side view thereof when viewing FIG. 4;

FIG. 7 is a sectional view taken along the section line 7-7 of FIG. 6; and

FIG. 8 is a sectional view taken along the section line 8-8 of FIG. 6.

The dominant features of the design are shown in solid lines.

I claim:

The ornamental design for a motor driven shoe polisher, as shown and described.
